Term of patent 14 years

Int. Cl. D13—01

U.S. Cl. D26—5

FIG.1

FIG.2

FIG.3

FIG. 1 is a side elevational view of a dynamoelectric machine employing my new design;

FIG. 2 is an end elevational view as seen from the left side of FIG. 1; and

FIG. 3 is an end elevational view as seen from the right side of FIG. 1.

The views of the dynamoelectric machine as seen from the top, bottom, and hidden side of FIG. 1 are not shown and are substantially similar to the illustration of FIG. 1.

I claim:

The ornamental design for a dynamoelectric machine, substantially as shown and described.
